United States Patent Office

Des. 223,902

Patented June 20, 1972

223,902

DOOR

Raymond L. Kuniansky, Atlanta, Ga., assignor to
Anaconda Aluminum Company

Filed Sept. 10, 1970, Ser. No. 24,914

Term of patent 14 years

Int. Cl. D25—02

U.S. Cl. D13—1

FIG. 1

FIG. 2

FIG. 3

FIG. 1 is a perspective of the door showing my new design;

FIG. 2 is an elevation of the left side vertical edge of the door of FIG. 1; and

FIG. 3 is a top plan view of the door of FIG. 1.

I claim:

The ornamental design for a door, as shown and described.
